Inventor
Nelson C. Cole

United States Patent Office.

NELSON C. COLE, OF BEAVER DAM, WISCONSIN, ASSIGNOR TO HIMSELF
AND LEVERETT H. MARVIN, OF SAME PLACE.

Letters Patent No. 97,764, dated December 14, 1869.

IMPROVED SASH-HOLDER.

The Schedule referred to in these Letters Patent and making part of the same.

Be it known that I, NELSON C. COLE, of the town of Beaver Dam, in the county of Dodge, and State of Wisconsin, have invented a new and useful Window-Lock; and I do hereby declare that the following is a full, clear, and exact description of the construction and operation of the same, reference being had to the accompanying drawings, and to the letters of reference marked thereon, making a part of this specification.

A A represent the face-plate;

B B represent the back-plate, extending at right angles with the face-plate;

C C represent the bolts;

D, the vibrating-lever;

E, the key-shafts;

F, the bolt-spring;

a a represent the window-sash;

b b, the jamb-casing;

d d represent the face-casing;

g, an adjustable key;

H H, the escutcheon; and

E o represent a skeleton knob-key.

Figure 1 is a sectional view of the sash and jamb-casing, giving a longitudinal elevation, showing as my invention, the plate D extending through the jamb b, the face of plate A being flush with the face of the jamb. On both sides of the plate D are placed the bolts C C, as shown, extending through plate A into the upper and lower sash a a, both being held in position by the bolts. To raise or lower the sash, either bolt may be thrown back by means of the vi-

brating-lever D, with the key. The force on the bolt being removed, the bolt is thrown into the sash again by the spring E. The lever D, on both sides of the plate B, is connected together through the plate, and with the aid of the key and key-shaft, either bolt or sash may be adjusted independent of the other.

Figure 2 is a perpendicular rear view, in which is shown the key-shaft E connected with the lever D, the key g being detached, leaving the outer end of shaft E unexposed within the escutcheon H, as shown in Figure 4, with the key attached.

Figure 3 is a horizontal sectional view of my invention, showing its position in the window-easing, a a representing the upper and lower sash, b b, the jamb, d, the face-casing, H, the escutcheon in the face-casing, and the key-shaft E, as permanently attached to a skeleton-knob. The key-shaft and skeleton-knob thus attached, form an independent adjustable key, which may be withdrawn at pleasure, leaving it perfectly secure.

What I claim as my invention, and desire to secure by Letters Patent, is—

The construction of a combination Window-Lock, with two bolts upon one plate, and operated by detachable keys, operating upon each sash independently, as herein described.

NELSON C. COLE.
